Patented June 9, 1925.

UNITED STATES PATENT OFFICE.

FRANK L. RICHARDSON, OF JENA, LOUISIANA.

SPRING GRIP LATCH FOR AUTOMOBILES, ETC.

Application filed August 26, 1924. Serial No. 734,307.

To all whom it may concern:

Be it known that I, FRANK L. RICHARDSON, a citizen of the United States, residing at Jena, in the parish of La Salle, State of Louisiana, have invented new and useful Improvements in Spring Grip Latches for Automobiles, Etc., of which the following is a specification.

The invention relates to a spring grip latch for automobile doors and various other kinds of closures and the like where a keyless grip latch is desirable.

The object of the present invention is to provide a simple, practical and efficient spring grip latch designed for use on automobile doors, barn doors, gates and various other kinds of closures and the like and capable of operation from the interior or exterior by a quick depression of an operating member and also of operation by a rotary actuated member and of being locked by the latter in an open position when desired.

It is also the object of the invention to provide a grip latch of this character which, when applied to automobile doors and the like, will present a neat and attractive appearance and not be liable to catch the clothes of persons entering or leaving a machine.

With these and other objects in view, the invention consists in the construction and novel combination and arrangement of parts hereinafter fully described, illustrated in the accompany drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a side elevation of a portion of an automobile body provided with a spring grip latch constructed in accordance with this invention.

Figure 2 is an enlarged detail elevation of the latch mechanism particularly in section.

Figure 3 is a vertical sectional view of the same substantially on the line 3—3 of Figure 2.

Figure 4 is a detail sectional view illustrating the construction of the keeper stud and the socket recess of the latch members.

Figure 5 is a detail view showing the socket recesses in the ends of the latch members.

In the accompanying drawing, in which is illustrated the preferred embodiment of the invention, the grip latch comprises in its construction, a pair of upper and lower latch members 1 and 2, but the latch members while shown in this position in the accompanying drawing, may of course be arranged in any other desired position as will be readily understood. The latch members are provided at an intermediate point with registering ears 3 and 4 through which passes a horizontal pivot pin 5 which is mounted in the door frame 6 and in a bearing of a bracket 7 secured to the door frame at the inner side thereof as clearly illustrated in Fig. 2 of the drawings. A pair of spaced ears 3 is provided on one of the members and a central ear 4 projects from the other member and is arranged between the ears 3 as shown.

The latch members are provided at their outer ends with heads 8 projecting beyond the frame of the door 9 or may be set back even with door frame and preferably concealed by a projecting plate 10, located at the outer side faces of the heads 8 of the latch members and adapted to be ornamented and forming a convenient means for receiving the initials of the owner of the car to which the latch is applied. Plate 10 may have a slot to insert letters that are already made. The cover plate or portion 10 may be of any configuration and if desired, may consist of an extension of the outer covering of the door. The heads 8 are provided with socket recesses 11, forming a socket for the reception of a headed stud 12, said stud may be made in right angle to fit inside of enclosures, constituting a keeper and preferably secured to a fixed portion of the body 13 of the automobile by means of an attaching plate 14 and designed to be arranged in a recess 15 as clearly illustrated in Fig. 4 of the drawing.

The socket recesses may be arranged in either side or a socket recess 15 may be provided in the outer ends of the heads of the latch members as illustrated in Fig. 5 of the drawing. This will enable the grip latch to be applied to various kinds of doors and also to sliding doors and closures.

The heads of the latch members are maintained in their engaging position in engage-

ment with the keeper stud 12 by means of a coiled spring 16 interposed between the rear portions or arms of the latch members and preferably engaged with projections 17 thereof as shown but any other suitable means may of course be employed for maintaining the spring in operative position interposed between the arms of the latch members and a spring of any desired size, shape and strength may of course be employed. The spring, when the upper latch member is open, will permit the keeper stud to readily disengage itself from the lower latch member and the said spring will also permit the ready automatic engagement of the latch members with the keeper stud when the door is closed. The recess 11 of the lower latch member has sufficient bevel to enable it to be automatically depressed by the keeper 12 when the head of the upper latch member is raised by one of the operating devices. This automatic operation of the lower latch member obviates the necessity of manually lifting the inner portion or arm of the same when opening the door.

The gripping latch is operated by inner and outer depressible operating rods 18 and 19 and also by a horizontal shaft 20, which extends to the exterior of the door and is provided at its outer end with a suitable handle 21 preferably consisting of oppositely extending operating arms. The inner depressible rod 18, which has its upper portion extending through a suitable guide 22, is provided at its upper end with a relatively small head 23 and it has a laterally extended horizontal arm 24 at its lower end located above and suitably secured to the upper latch member at 25 as clearly indicated in Figures 2 and 3 of the drawing. The inner depressible operating rod is sufficiently small and out of the way to avoid any liability of the clothes of a person accidentally catching on it while entering or leaving the machine, and the upper end of the operating rod 18 preferably terminates short of the upper edge of the door 9.

The outer operating rod 19 which is guided in the upper portion of the door frame as shown, rests upon the upper face of the arm of the upper latch member and it extends above the car door and is provided at its upper end with a head 26 which is adapted to be readily depressed from the exterior for operating the latch to open the door. The horizontal shaft 20 is provided with a cam 27 preferably in the form of a disk eccentrically secured to the shaft and arranged to engage the upper face of the arm of the upper latch member whereby when the shaft 20 is rotated by turning the handle 21, the arm of the latch member 1, will be depressed to disengage the head of the latch member from the keeper stud. 85 This will permit the door to be readily un-

latched from the exterior by means of the handle 21 and the shaft and the cam are adapted to maintain the arm of the upper latch member in a depressed condition against the action of the spring. When the cam 27 is rotated to release the arm of the latch member 1, the spring 16 will operate to close the head of the upper latch member against the head of the lower latch member. The arm of the lower latch member 2 is seated upon a suitable stop or support 28, which may be formed in the frame of the door as shown in Fig. 2 or in any other desired manner.

What is claimed is:

1. A grip latch including a pair of upper and lower latch members pivoted at an intermediate point and provided with outer heads having recesses forming a socket adapted to receive a keeper to permit the latch members to engage the same, the inner portions of the latch members forming arms, a spring interposed between the arms and adapted to maintain the heads in engagement with the keeper, inner and outer depressible rods arranged to engage one of the said arms for releasing the latch and a horizontal shaft having a cam located above and arranged to engage an arm of the upper latch members for operating the same, the lower latch member being adapted to be operated automatically by the keeper when the upper latch member is operated to disengage it from the keeper.

2. A grip latch comprising a pair of latch members pivoted intermediate of their ends and provided at their outer portions with heads having co-acting recesses forming a keeper receiving socket, a spring interposed between the latch members at the inner side of the pivot thereof, a stop receiving the inner end of one of the latch members and operating means arranged to engage the other latch member for releasing the latch.

3. A grip latch comprising a pair of latch members pivoted intermediate of their ends and provided at their outer portions with heads having co-acting recesses forming a keeper receiving socket, a spring interposed between the latch members at the inner side of the pivot thereof, a stop receiving the inner end of one of the latch members, an inner operating rod having an arm secured to the other latch member at the inner portion thereof, an outer operating rod arranged to engage the latch member to which the inner rod is secured and arranged for operation exteriorly of a closure and a shaft having a cam for engaging the said latch member and provided with an exterior handle.

In testimony whereof I have hereunto set my hand.

FRANK L. RICHARDSON.
